(57) **CLAIM**

The ornamental design for a ladder hand rail, as shown and described.

DESCRIPTION

FIG. 1 is a front perspective view of a ladder hand rail showing my new design;

FIG. 2 is a front elevation view thereof;

FIG. 3 is a rear elevation view thereof;

FIG. 4 is a left side elevation view thereof;

FIG. 5 is a second right side elevation view thereof;

FIG. 6 is a top plan view thereof; and,

FIG. 7 is a bottom plan view thereof.

The ladder hand rail is shown with a symbolic break in its length. The appearance of any portion of the article between the break lines forms no part of the claimed design.

The broken lines shown in the figures are for the purpose of illustrating portions of the ladder hand rail that form no part of the claimed design.
